DESIGN.

G. A. BRACHHAUSEN.
MUSIC BOX COVER.

No. 26,485.

Fig. 1. Patented Jan. 5, 1897.

UNITED STATES PATENT OFFICE.

GUSTAV A. BRACHHAUSEN, OF RAILWAY, NEW JERSEY.

DESIGN FOR A MUSIC-BOX COVER.

SPECIFICATION forming part of Design No. 26,485, dated January 5, 1897.

Application filed November 30, 1896. Serial No. 614,009. Term of patent 14 years.

To all whom it may concern:

Be it known that I, GUSTAV A. BRACHHAUSEN, a subject of the Emperor of Germany, residing at Rahway, Union county, in the State of New Jersey, have invented and produced a new and original Design for Music-Box Covers, of which the following is a specification, reference being had to the accompanying drawings, wherein—

Figure 1 represents a top view of a cover for music-boxes embodying my design. Fig. 2 is an edge view of the same. Fig. 3 is a transverse sectional view of the same on the line 3 3 of Fig. 1.

The essential characteristics of my design consist in a cover for music-boxes having a base with a central opening therein, a cap, and grillework extending between said cap and base.

In the drawings, A represents a base on the

music-box cover, which is provided with a central opening *a*. Mounted above the base A is a cap B, which has a grille C intervening between it and the base. Said grille preferably consists of ornamental pillars *b*, having openings *c* between them, so that open passages are provided for sound-waves through the base of the cover and between the grille C. 25

Corner ornaments D may be provided at the corners between the base and cap. 30

What I claim is—

The design for music-box covers, having a base, a cap above said base, and grillework intervening between said base and cap, substantially as shown and described.

GUSTAV A. BRACHHAUSEN.
